(57) **CLAIM**

The ornamental design for a pair of aircraft windows, as shown and described.

DESCRIPTION

FIG. 1 is a perspective view of a pair of aircraft windows showing our new design;

FIG. 2 is a top plan view thereof;

FIG. 3 is a side elevational view of one side thereof;

FIG. 4 is a side elevational view of the other side thereof;

FIG. 5 is a detailed top plan view of the portion of the fuselage showing the pair of aircraft windows;

FIG. 6 is a bottom plan view of the area shown in FIG. 5; and,

FIG. 7 is a cross sectional view shown along line 7-7 of FIG.

6.

The broken line showing of the elongated oval in FIG. 5 illustrates a hidden line. The broken line showings of the remainder of the aircraft form no part of the claimed design.
